UNITED STATES PATENT OFFICE.

ALBERT L. HARRIS, OF BAY CITY, MICHIGAN, ASSIGNOR TO KELTON AURAND MANUFACTURING CO., OF BAY CITY, MICHIGAN, A CORPORATION OF MICHIGAN.

ADJUSTABLE RECLINING CHAIR.

Application filed October 17, 1927. Serial No. 226,602.

This invention relates to adjustable chairs, and particularly to a chair for use in cross country busses, street cars, airplanes and passenger carrying vehicles in general.

5 The prime object of the invention is to provide a chair on which the angle of inclination of the back rest can be quickly and easily adjusted.

Another object is to provide means for supporting the back frame in its various adjusted positions.

10 A further object is to design an adjustable reclining chair, particularly adaptable for two passenger seats, and which permits of 15 independant adjustment of one or both of the back frames as desired, and without interfering with passengers either ahead or behind, or the passenger occupying the other half of the double seat.

20 A further object still is to provide an adjustable reclining chair which is easy to manufacture, which will be rigid and substantial in any adjusted position, which is of neat and pleasing appearance, as well as very 25 comfortable.

The above and other objects will appear as the specification progresses, reference being had to the accompanying drawings in which I have shown the preferred embodiment of my 30 invention, and in which like reference numerals indicate like parts throughout the several views thereof.

Fig. 1 is a side view of my improved adjustable reclining chair.

35 Fig. 2 is a back view thereof.

Fig. 3 is an enlarged fragmentary side view of the upper and lower members which form the joint or hinge in the back frame.

40 Fig. 4 is a front view of the members shown in Fig. 3.

Fig. 5 is an enlarged fragmentary side view showing the joint or hinge assembled, the dotted lines showing the top of the frame in adjusted reclining position.

45 Fig. 6 is a side view of one of the back braces, the dotted lines showing the position of the brace when the back is reclined.

Fig. 7 is an edge view thereof.

50 Fig. 8 is a sectional plan view taken on the line 8—8 of Fig. 5.

Fig. 9 is a side view of one of the link pins.

55 Fig. 10 is an enlarged fragmentary top plan view of one of the arm rests, showing the strap and pin with which the toothed lever engages.

Fig. 11 is an enlarged side view of the tooth lever.

Fig. 12 is a top plan view thereof.

Referring now particularly to the drawing in which I have shown the preferred embodiment of my invention, the numeral 5 indicates a chair which can be formed of wicker, cloth, leather, or any other desired material, this chair is provided with the usual arm rests 6, shaped as clearly shown in Fig. 1, of the drawings, the back frame 7 being jointed or hinged at 8 to permit of the adjustment thereof, this hinging joint being preferably at a point in line with the top of the cushion.

The chairs are designed to accomodate 70 two people, the passengers sitting side by side with no division wall or partition between them, consequently, adjustment must be from the sides of the chair only. The back frame is preferably made up of a seamless 75 tubing, bent as shown, and a short section of rolled steel 9 is inserted in the ends and is secured in position by means of a rivet 10 in the usual manner, the lower end of said section being shaped to form a tongue 11, provided with a transversely disposed opening 12 therein, the one edge being cut at an angle as shown at 13 to permit of movement as will be hereinafter described.

Similar tubing 14 is secured to the arm 85 rests by means of bolts 15, the lower end of the tubes being flattened, and are secured to the bottom of the chair, a short section of rolled steel 16 being inserted in the upper end, and is held in place by a rivet 17 as usual, the upper end of the member 16 being shaped to 90 form spaced apart legs 18, having an opening 19 extending therethrough, the upper corners being cut as shown at 19^a so that when the frame is assembled, the upper section can be swung without interference, the angle portion 13 of the tongue 11 forming a stop to limit the movement of the back frame as clearly shown in Fig. 5 of the drawing.

A lever 20 is pivotally connected to one leg 100 of the back frame at a point spaced from the joint by means of the bolt or rivet 21, the free end extending at an angle, and is received between the arm rest and a bar member 22, which is secured to said arm rest, the ends of 105 the bar being bent and secured to the arm rest by means of bolts or rivets 23. A transversely disposed pin 24 is mounted in the arm rest and bar member respectively, the free end of the lever being provided with 110

teeth 25 for engaging said pin, a coiled spring 26 being anchored to the end of the bar and chair frame respectively, for holding the teeth in engagement with the pin, and a suitable handle is provided on the lever to facilitate adjustment.

The opposite leg of the frame is braced and held by means of a bowed brace 27, the lower end being pivotally connected to the frame 10 at 28, the upper end being provided with a cam shaped head 29 terminating in a pocket 30, a link member 31 is pivotally connected to the head as shown, the opposite end being pivotally mounted on the shoulder 32 of the 15 pin 33, said pin being securely mounted in the back frame and is provided with a head 34 which engages the cam shaped edge of the head, said link and head being in position as shown in full lines in Fig. 5 of the drawings 20 when the back is in upright position, rolling into the pocket 30 when the back is adjusted to reclining position, the bowing of the member 27, together with the fact that the head 34 engages the cam edge at all times, provides 25 a firm support in all positions, and which automatically shifts when the adjustment takes place.

From the foregoing description it will be obvious that I have perfected a very simple, 30 comfortable, and substantial chair, which can be adjusted as desired, which has no complicated mechanism or parts, and which can be easily made and assembled.

What I claim is:—

35 1. An adjustable reclining chair comprising a seat frame, a back frame hingedly secured thereto, a toothed lever pivotally connected to one side of the back frame and detachably engaging the seat frame, an outwardly bowed brace pivotally connected to the seat frame, and a substantially horizontally disposed link connection between the upper end of the brace and the back frame.

45 2. An adjustable reclining chair comprising a seat frame, a back frame hingedly connected thereto, a lever connected to one side of the back frame and having detachable connection with the seat frame, a bowed brace pivotally connected to the opposite side of 50 the seat frame, a link connection between the upper end of said brace and the back frame, and a pocket on the brace for engaging the back frame when the back is in extreme reclining position.

55 3. An adjustable reclining chair comprising

ing a seat frame, a back frame hingedly secured thereto, a toothed lever connected to one side of the back frame and detachably engaging the seat frame, and a vertically disposed brace pivotally secured to the seat frame, the upper end being provided with a cam shaped edge, a link connecting said frame and head, and a pin connecting the link to the frame and provided with a head which rolls on and engages said cam shaped edge. 65

4. An adjustable reclining chair comprising a seat frame, a back frame hingedly connected thereto, a toothed lever connected to one side of the frame and detachably engaging the seat frame, and a vertically disposed brace pivotally connected to the opposite side of the seat frame and formed with a head having a rounded edge terminating in a pocket, a link pivotally connected to the head, a pin connecting the opposite end of the link to the frame and provided with a head and adapted to engage said rounded edge and rest in said pocket when the back frame is set in predetermined position. 70

5. An adjustable reclining chair comprising a seat frame, a back frame hingedly secured thereto, a toothed lever pivotally connected to one side of the back frame and detachably engaging the seat frame, a bowed brace pivotally secured to the opposite side 85 of the seat frame, said brace being formed with an offset head having a rounded edge terminating in a pocket, a link connected to said head, a pin connecting said link and back frame and provided with a head which engages said rounded edge for holding the back frame in adjusted position. 90

6. An adjustable reclining chair comprising a seat frame, a back frame hingedly secured thereto, said hinge comprising upper 95 and lower tubular sections, a tongue on the upper section, and ears on the lower section adapted to receive the tongue therebetween, a pin pivotally connecting the tongue and ears together, the lower end of the tongue 100 having an angled portion adapted to form a stop, a toothed lever pivotally connected to the back frame and detachably engaging the seat frame, and a vertically disposed brace member on the opposite side of the frame, 105 and having pivotal connection with the seat frame and back frame respectively.

In testimony whereof I hereunto affix my signature.

ALBERT L. HARRIS.
